UNITED STATES PATENT OFFICE

HYMAN HENDEL, OF BROOKLYN, NEW YORK

NECKTIE

Application filed April 23, 1930. Serial No. 446,606.

This invention relates to improvements in neckties, and more particularly it pertains to made-up neckties of bow form.

It is one of the objects of the present invention to provide a novel form about which a bow tie may be formed, and which includes means to maintain the loops of the knots of a bow tie at all times extended.

It is a further object of the invention to provide novel means for maintaining the loops of the knots at all times in extended position and prevent crushing thereof.

It is a further object of the invention, to provide novel means for securing the bow extending means in position in the body portion.

With the above and other objects in view, reference is had to the accompanying drawings, in which:

20 Figure 1 is a view in front elevation of a necktie formed about a body portion constructed in accordance with the present invention,

25 Figure 2 is a view in elevation of the form about which the tie is formed, with a portion of the form turned back to expose the interior thereof,

Figure 3 is a detail sectional view taken on the line 3—3 of Figure 2.

30 Referring specifically to the drawings, the reference character 5 designates the knot of a bow necktie, and this knot 5 may be secured in any desired manner to a neck band 6.

35 The knot 5 is formed about a form or lining such as illustrated in Figure 2 of the drawings. This lining comprises two members 7 and 8 of substantially complementary form. These members 7 and 8 are formed from semi-rigid material such as buckram, canvas or the like, and are secured together in face to face relation by means of a line of stitching 9 which extends entirely around the body adjacent the edge thereof as illustrated in Figure 2.

The form is provided at each end with a pocket 10, and adapted for reception in the pocket 10 there are means which serve to maintain the loops of the knot at all times extended. These means as shown in the

present illustration of the invention, preferably comprise coil springs 12 which extend transversely of the form, and which when positioned in the pocket form bulged portions 13 at opposite ends of the form, which bulged portions extend transversely of the body of the form.

The pockets 10 may be formed by transversely stitching the form as indicated at 15 at points slightly removed from the end of the form, and these lines of stitching together with the stitching 9 which extends along the end edges of the form provide the spaces or pockets 10 heretofore referred to.

From the foregoing it will be apparent that the bulged portions 13 of the form serve to maintain the loops of the knot of the tie at all times extended, and that any crushing of the tie is prevented by reason of the coil springs 12 which serve to return the loops of the knots to their original position when they are crushed.

While the invention has been herein illustrated in a preferred form, it will be obvious that the same may be executed in other forms which fall within the scope of the hereto appended claim.

Having thus described the invention, what is claimed, and desired to secure by Letters Patent of the United States, is:—

A form for the manufacture of made up neckties of bow form, including a body portion comprising two substantially complementary members secured in face to face relation, a pocket formed by lines of stitching adjacent each end of the body portion, a bow extending means in each of said pockets, said means comprising a coil spring secured in each of said pockets.

In testimony whereof I affix my signature.

HYMAN HENDEL.
